UNITED STATES PATENT OFFICE.

GEORGE M. EAMES, OF BRIDGEPORT, CONNECTICUT.

EDGE-FINISHING AND UNITING WOVEN FABRICS.

1,305,528

Specification of Letters Patent.

Patented June 3, 1919.

Application filed August 24, 1918. Serial No. 251,319.

To all whom it may concern:

Be it known that I, GEORGE M. EAMES, a citizen of the United States, residing at Bridgeport, in the county of Fairfield and State of Connecticut, have invented certain new and useful Improvements in Edge-Finishing and Uniting Woven Fabrics, of which the following is a specification, reference being had therein to the accompanying drawings.

This invention relates to new and useful improvements in edge-finishes for collars, cuffs and like articles made of woven materials.

It is a common practice to finish edges of fabrics by folding and hem-folding the same or by applying a binding strip to a fabric with or without a folded edge. When the fabric is of any appreciable thickness, the edge, finished according to known methods, presents a bulky, unsightly appearance.

The present invention has for its object to improve the known methods of edge-finishing fabrics by providing the woven material with a margin of less thickness than that of the body of the material, and then folding the comparatively thin margin upon itself, upon the body-material, or both and securing the fold in a suitable manner.

In a specific embodiment of the invention, a collar may be cut out of a ribbon or strip of woven material, as disclosed and described for instance in the U. S. patent to Bowen, No. 1,254,306, dated January 22, 1918. The raw margin of the collar may be skived or scarfed to produce a margin of less thickness than that of the body-material and the skived margin may then be folded and the fold secured in any suitable manner, but preferably by a line or lines of stitching. The resulting product is neat in appearance and presents no unsightly ridge at its margin, for when ironed the fold practically merges into the body of the collar to an extent leaving the fold scarcely perceptible.

In the accompanying drawings, which illustrate a specific embodiment of the invention, Figure 1 is a plan view of a cut-out collar blank and illustrating the several edge-finishing stages. Figs. 2, 3 and 4 are enlarged sectional views taken respectively on the lines $x-x$, $y-y$ and $z-z$, of Fig. 1. Fig. 5 is a modification, illustrating a sectional view of a collar with the skived edge hem-folded upon itself, and Fig. 6 is an en-

larged diagrammatic cross section of a multi-ply fabric, of which a portion is skived.

Referring to the drawings, a collar blank 1 is cut with the desired shape and proportions from a strip or ribbon of comparatively heavy interwoven material. The free edge 2 of the blank if hem-folded would form an unsightly, bulky seam, while the binding of the raw edge with a narrow tape is not only difficult of accomplishment around the sharp corners of the collar, but produces a seam disagreeable to the sight at the juncture of the ends of the tape and at the meeting tabs of the collar.

In accordance with the present improved method of finishing the edge of the collar, the free edge or margin 2 of the blank is skived or scarfed to produce a thinned edge 3. The skived edge 3 is then folded or hem-folded and united with the body of the collar in any preferred manner, preferably employing either one or two lines of stitching as 4. Two different methods of folding the skived margin are illustrated in Figs. 3 and 5 of the drawings. The fold 5, when the collar is ironed, leaves a scarcely perceptible ridge on the body of the collar, the fold appearing on the inside edge of the collar when the panels of the latter are folded in the usual manner for use, while only the stitching shows on the outer surface of the collar, giving to the latter a desirable appearance. It is of course obvious that the folded portions of the material may be united without employing stitching, as for instance by cement.

The provision of a thinned edge at the margin of the collar by the preferred method described, namely by skiving, is particularly feasible in multi-ply fabric woven as a single piece, as described in Patent No. 1,254,306 herein referred to. This is illustrated in Fig. 6 of the accompanying drawings, in which a two-ply woven fabric, comprising warp-threads 6 and 7, and weft threads 8 and 9 are woven as individual complete plies separated by a filling thread 10 and united by a binding thread 11. It is apparent that in fabrics of this kind one or more of the plies may be skived, as shown in the drawings without destroying the remaining ply or plies.

While the present improvement is illustrated in the accompanying drawings as a collar edge finish, applicant believes he is

the first to employ an edge-finish of this kind in interwoven materials used for any purpose and desires it to be understood that, broadly considered, the invention is not limited in its application to the article shown.

Having thus set forth the nature of the invention, what I claim herein is—

1. An improved edge finish for collars and like articles made of interwoven multiply fabric having a thinned margin, said thinned margin being folded and secured to the body-fabric to produce a finished edge of substantially the same thickness as that of the body of said fabric.

2. An improved method of making collars, consisting of cutting the collar blanks from a strip of multiply fabric woven as a single piece, thinning the margins of the blanks by skiving one or more of the multiple plies, hem-folding the thinned margins, and securing the hem-folds by a line of stitching to thereby obtain a finished edge of substantially the same thickness as that of the body of said collar.

In testimony whereof, I have signed my name to this specification.

GEORGE M. EAMES.
